UNITED STATES PATENT OFFICE.

WILLIAM SHIRLEY CARTER, OF LOVINGSTON, VIRGINIA.

KNOCKDOWN BARREL OR HOGSHEAD.

1,223,767.

Specification of Letters Patent. Patented Apr. 24, 1917.

Application filed September 30, 1915. Serial No. 53,311.

To all whom it may concern:

Be it known that I, WILLIAM SHIRLEY CARTER, a citizen of the United States, residing at Lovingston, in the county of Nelson and State of Virginia, have invented certain new and useful Improvements in Knockdown Barrels or Hogsheads, of which the following is a specification.

My invention contemplates certain new and useful improvements in crates, barrels, hogsheads and the like, and resides more especially in a novel form of fastening means for securing the several parts in a set up position.

15 My improved fastening means is preferably designed for use in connection with a barrel or hogshead as shown in United States Patent Number 1,148,355 granted to me July 27, 1915, and has for an object the provision 20 of an adjustable means carried by the heads or ends of the barrel whereby the several staves can be drawn inwardly and securely attached to the heads as will more fully hereinafter appear.

25 Another object of my invention is to provide a simple, cheap and efficient fastening device which can be readily attached to the heads or ends of the barrel, and then connected to the surrounding staves to hold the 30 same in set up position.

A further object of my invention is the provision of a fastening device including a locking means for holding the said fastening device in its adjusted position.

35 With these and other objects in view my invention further resides in the novel arrangement and combination of parts herein-after described and pointed out in the appended claims.

40 In the drawings which show by way of illustration one embodiment of my invention:

Figure 1 is a top plan view of my improved fastening means as applied to a barrel or hogshead.

Fig. 2 is a fragmentary view in perspective of one of the fastening devices, and

Fig. 3 is a detail sectional view through the upper portion of a barrel with my fastening device in position.

The invention as set forth in the accompanying drawing is primarily designed for use upon hogsheads or barrels which are composed of a plurality of radially arranged 55 staves held at intervals against the edges of the end or head closures. In the commer-

cial handling of containers of this class, it has been found that the knockdown type of barrel or hogshead is the most serviceable and practical, and as a successful and economical fastening means for the several parts is required in such structures, the hereinset-forth invention has been designed.

The fastening device of which several are usually applied, comprises a base or plate 1 suitably secured as at 2 by rivets, screws or other means to the ends or heads 3 of the hogshead or barrel 4. Rotatably mounted upon the base or plate 1 is a disk member 5. This member 5 is positioned upon the stud 6, and is provided on one side at the edge thereof with an engaging hook 7. This hook may be formed integral with the disk member as shown, or otherwise suitably secured thereto in any desired manner. At a point substantially diametrically opposite the said hook 7, there is provided on the member 5 a plurality of teeth or segmental mutilations 8 as clearly shown. These teeth are preferably in the form of ratchet teeth 80 and are designed to coöperate with a spring actuated pawl 9 pivotally secured to the base or plate at 10.

The spring 11 normally forces the said pawl into engagement with the ratchet teeth 85 as will be readily understood.

The operating means for the fastening device comprises in part suitable projecting studs 12 provided on the disk member 5, and between which a bar or other lever actuating instrument may be positioned when the disk is to be rotated in the positioning of the staves against the end closures.

Coöperating with and connected to the fastening devices just described are links 13, the inner ends 14 of which are engaged by the hooks 7, and the outer ends of which receive the encircling hoops or bands 15 of the barrel or hogshead. These links are designed to pass through openings 16 formed in the relatively spaced staves, as clearly shown in Fig. 3 of the drawing.

In assembling the several parts of the barrel or hogshead by means of my improved fastening devices, the relatively spaced staves are positioned against the head or end closures and the encircling hoops threaded with the several spaced and positioned links 13. The ends of the encircling hoops or bands are preferably connected by a turnbuckle or other adjustable connecting device 17, as shown in Fig. 1, which is, how-

ever, suitably loosened at the out set of the assembling. The inner ends of the links 13 are now in turn engaged by the hooks 7 and the intervening or connecting staves properly positioned between the hereinbefore referred to relatively spaced staves. As the staves are successively positioned around the barrel or hogshead, the disk members 5 of the fastening devices are successively rotated by means of the studs 12, or a bar placed between the said studs, thereby drawing in the links 13 and the hoops or bands 15 and firmly securing the staves against the end or head closures.

15 During the rotation of the disk members 5 of the fastening devices, the pawls 9 ride over the ratchet teeth 8, but when the desired position of the staves and fastening devices has been obtained the springs 11 force 20 the pawls into engagement with the said teeth and prevent the rotation of the disk members in an opposite direction, thereby effecting a positive fastening and positioning of the barrel or hogshead when set up.

25 From the foregoing it will be obvious that I have provided an efficient and readily attached fastening means capable of easily effecting the positioning of the several staves of a barrel or hogshead, and securing in addition thereto a relative adjustment of the said staves and a locking of the parts in the adjusted position as occasions require.

Having thus described my invention, what I claim and desire to secure by Letters 35 Patent is:

1. A container comprising staves having adjustable hoops for sustaining the same against outward movement, heads arranged within the opposite ends of the staves to 40 sustain the same against inward movement,

means including adjustable hooks connected to the end hoops, and means for holding the said hooks in adjusted position.

2. A container comprising staves having adjustable hoops for sustaining the same 45 against outward movement, heads arranged within the opposite ends of the staves to sustain the same against inward movement, links upon the end hoops and arranged upon the outer faces of the heads, and means including adjustable hooks upon the heads for engaging the said links.

3. A container comprising staves having adjustable hoops for sustaining the same 55 against outward movement, heads arranged within the opposite ends of the staves to sustain the same against inward movement, links upon the end hoops, means including rotatable hooks upon the heads for engaging the inner ends of the said links, and 60 means for engaging the said hooks and securing them in adjusted positions.

4. A container comprising staves having adjustable hoops for sustaining the same 65 against outward movement, heads arranged within opposite ends of the staves to sustain the same against inward movement, links upon the end hoops passing through openings in certain of the staves and arranged upon the outer faces of the heads, and 70 means including rotatable hooks and locking pawls for securing them in adjusted positions.

In testimony whereof I affix my signature in presence of two witnesses.

WILLIAM SHIRLEY CARTER.
